(57) CLAIM

The ornamental design for a utensil as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a utensil according to my new design;

FIG. 2 is a rear elevation view thereof;

FIG. 3 is a front elevation view thereof;

FIG. 4 is a right side elevation view thereof, the left side being a mirror image thereof;

FIG. 5 is a bottom plan view thereof;

FIG. 6 is a top elevation view thereof;

FIG. 7 is a perspective view of another version thereof; and

FIG. 8 is a perspective view of still another version thereof.

FIG. 9 is a perspective view of a utensil according to my new design;

FIG. 10 is a rear elevation view thereof;

FIG. 11 is a front elevation view thereof;

FIG. 12 is a right side elevation view thereof, the left side being a mirror image thereof;

FIG. 13 is a bottom plan view thereof;

FIG. 14 is a top elevation view thereof;

FIG. 15 is a perspective view of another version thereof; and,

FIG. 16 is a perspective view of still another version thereof.

The dash-dash lines of the figures unclaimed elements of the design and form no part of the claimed design. The dash-dot-dash lines of FIGS. 1-4, 7-8, 9-12, and 15-16 depict the boundaries of the claimed features and form no part of the claimed design.
